A. LAMM ET AL

ROOF STRUCTURE

Filed Apr. 7, 1921

Anthony Lamm Inventor
John S. Schroeder
By their Attorney
Ivan E. Karpisberg

UNITED STATES PATENT OFFICE.

ANTHONY LAMM, OF BROOKLYN, AND JOHN F. SCHROEDER, OF MIDDLE VILLAGE,
NEW YORK.

ROOF STRUCTURE.

Application filed April 7, 1921. Serial No. 459,349.

To all whom it may concern:

Be it known that we, ANTHONY LAMM, a citizen of Germany, and residing in Brooklyn, Kings County, New York, and JOHN F. SCHROEDER, a citizen of the United States, and residing in Middle Village, Queens County, New York, have invented certain new and useful Improvements in Roof Structures, of which the following is 10 a specification.

This invention relates to shingles and methods of laying the same for roofing and other purposes. More particularly this invention relates to a novel and improved 15 method of laying shingles of the type in which one corner of the shingle is bent and caught under adjacent shingles in order to provide a surface or roof consisting of a layer of overlapping and interlocking 20 shingles with means for securing them to the roof.

The broad object of the invention is to provide a novel method for laying the shingles whereby the cost of making the 25 shingles as well as the cost of laying them is much reduced and the work materially simplified.

The features of the invention will be more readily understood from the following description read in connection with the accompanying drawing in which—

Fig. 1 illustrates our improved method of laying shingles on a roof.

Fig. 2 is a perspective view showing a 35 few shingles to more clearly illustrate the invention.

Figs. 3 and 4 are face and edge views of one form of shingle used.

Figs. 5 and 6 are face and edge views of 40 another form of shingle used.

In carrying out our invention we employ eave or edge shingles to start the work with. As shown in Figures 3 and 4, the eave 45 shingle 10 is in the form of a rectangularly shaped shingle which is bent back upon itself at the edge 11. The portion 12 forms a top layer and the portion 13 forms a bottom layer. The corners of the top layer 12 are cut off at 14 adjacent the edge 11.

50 The roofing proper consists of what may be called lattice shingles which as shown in Figures 5 and 6 consists each of a shingle 16 preferably in the form of a square, one corner of which as 17 is bent back upon the

body 16 of the shingle. The corner 17 55 forms a hook at the one corner of the shingle.

For purposes of identification and not as a limitation the shingles 10 will hereinafter be called starter shingles and the shingles 16 will be called lattice shingles. The shingles are preferably of asphalt, asbestos, composition or other suitable material. The forms illustrated in Figures 3 to 6 are the ones in which the shingles are manufactured.

A shingle roof consisting of artificial shingles as aforesaid may be laid over an old natural shingle roof if desired. However, the better practice is to lay a foundation roof of planks or boards. This feature is known in the art. For the purpose of understanding this invention the reference numeral 20 in Figure 1 denotes a roof or foundation suitably prepared to afford a substantially smooth or even surface upon which to lay the shingles.

In laying the shingles the following method is carried out.

First the center of the roof is ascertained and marked. In the drawing the center of the roof is at 21. Thereafter the roof is strung with wires which run parallel to the eave or edge 22 of the roof and which are spaced evenly as shown a distance apart 75 equal to the distance between each layer of shingles as hereinafter will appear.

Any suitable wire may be used and it may be a continuous wire as indicated or each strand or length of wire may be separate. 80 Suitable fastening means such as nails 23 may be used. It will be noted that there is a strand of wire 24 adjacent the lower edge of the roof.

Thereafter the starter shingles are laid 85 by hooking the bent edge 11 over the lowermost wire 24, see also Figure 2, the adjacent sides of the two first starter shingles meeting on the line 21. Thereafter the shingles 10 are laid alongside each other from the center outward. Each shingle is nailed 90 as at 25, 25 and the top layer 12 is slipped under the second wire 26.

Next the lattice shingles 16 are laid by placing the first one over the joint at 21 (in 105 the drawing this particular shingle is removed) and hooking the hook 17 under the exposed portion of the wire 24 which appear

between adjacent starter shingles where their corners 14 are cut away and said first lattice shingle is then nailed at 27, 27.

Next the second lattice shingle is laid over 5 the next joint 28 between the next two starter shingles and so forth. It will then be seen that the wire 24 has been completely covered and serves as a means for keeping the lowermost row of shingles to the roof 10 and more particularly serves a means for placing said shingles in alinement. It will also be seen that after the first row of shingles 10 and 16 has been laid there is an exposed portion of wire 26 between each two 15 adjacent shingles 16.

Thereafter the second row of lattice shingles are placed in position by hooking the shingle hook portion 17 over the exposed portions of the wire 26 and said second row 20 of shingles, marked 30, 30 in Figure 1 covers the spaces between adjacent shingles in the first row.

In this manner the entire roof is covered with shingles, each shingle overlapping the 25 two adjacent shingles in the preceding row. Each shingle is nailed separately as shown at 27, 27. The edge of the shingles at 31 is cut off and the roof finished in any suitable manner known to the art. This also applies 30 to the hip of the roof.

In laying the shingles as aforesaid it will be seen that the work of aligning the shingles and spacing them is practically eliminated in that the shingles align themselves 35 automatically by being hooked over the wires 24, 26 and so forth.

These wires therefore serve primarily and

mainly as a spacing and aligning means. Secondarily the wires serve to tie all the shingles together as is obvious.

This method of laying shingles is therefore characterized by great speed, accuracy and the use of shingles which do not require hooks, wires or other means in order to attach one shingle to another. It is further 45 characterized by the fact that the spacing and aligning means are common to each row of shingles and is placed on the foundation in advance of the shingles.

We claim:—

In a roof structure the combination with a foundation, of starter shingles laid thereon at the edge of the roof, said starter shingles consisting of an upper portion and a lower portion bent back beneath the upper portion, a spacing wire secured to said foundation and passing through all of said starter shingles between the upper and lower portions thereof, said starter shingles having the lower corners of their upper portions cut away to expose a portion of the said spacing wire therebetween, lattice shingles having means for engaging the said exposed portions of the wire passing through the starter shingles to cover the joints therebetween to form a first row of shingles, other lattice shingles similar to the lattice shingles aforesaid and adapted to be laid in successive rows to cover the said foundation and other spacing wires adapted to engage 60 the said other lattice shingles to align the same in regular rows.

ANTHONY LAMM.
JOHN F. SCHROEDER.
